COMBINATION CAMERA AND PAIR OF SPECTACLES OR SIMILAR ARTICLE

Harry E. Giesecking and Albert F. Quinlan, St. Louis, Mo.;
assignors to W. A. Sheaffer Pen Company, Fort Madison,
Iowa, a corporation of Delaware

Filed Jan. 6, 1964, Ser. No. 78,082

Term of patent 14 years

(Cl. D57—1)

FIG. 3

The rear side of the article is plain and unornamented, and the dominant features of our design reside in the parts shown in full lines.

We claim:

The ornamental design for a combination camera and pair of spectacles or similar article, as shown and described.
